UNITED STATES PATENT OFFICE.

WILLIAM S. LACKEY, OF HADDONFIELD, NEW JERSEY, ASSIGNOR TO HIMSELF AND CLARENCE A. KROUSE, OF SAME PLACE.

FIRE-PAIL.

SPECIFICATION forming part of Letters Patent No. 624,505, dated May 9, 1899.

Application filed January 11, 1899. Serial No. 701,878. (No model.)

To all whom it may concern:

Be it known that I, WILLIAM S. LACKEY, a citizen of the United States, residing at Haddonfield, in the county of Camden and 5 State of New Jersey, have invented certain new and useful Improvements in Fire-Pails, of which the following is a specification.

My invention relates to fire-pails of that class which are adapted to contain an extinguishing fluid and are intended to be used as an ordinary pail in throwing the fluid upon the fire. It is important that the pail should be closed to the outside air, so as to prevent evaporation of its contents, and, further, that 15 its closure should be waterproof, and in carrying out my invention I have aimed to produce a pail with a simple form of closure adapted to attain both of the objects stated.

My invention includes, in a pail of substantially ordinary form, a top of tin-foil cemented about its edge by a non-drying adhesive material supported about the upper edge of the pail within its circumference, a particular means of supporting this cement 25 filling, and, finally, it includes a protecting cover, the tin-foil held in place upon the pail by means of a spring-flange allowing this cover to be easily and quickly displaced when occasion requires.

30 In the accompanying drawing, the figure is a sectional view of a pail made in accordance with my present invention.

In the figure, A represents the pail, which may be of any ordinary construction and of a proper size. Its walls are preferably flaring and especially at its upper part, and into this flaring part a ring B fits, having straight walls and forming a V-shaped space between the outer wall of the ring and the inner face 35 of the upper edge of the pail, and into this space I place an adhesive cement, which may be of any suitable composition, preferably of the non-drying character.

In order to seal the contents of the pail and 45 make it both air and water tight, I provide a cover of tin-foil D, the edges of this tin-foil being pressed into close sealing contact with the cement, and thus not only securing it but making a tight connection. The pail has preferably a beaded or turned-over edge E. In 50 order to protect the tin-foil from abrasion and

rupture, I provide a supplemental protecting-cover F, having a flange of slightly curved form and adapted to spring over the beaded edge of the pail and to be held in place 55 without other fastening means than its own resiliency. This cover is provided with a loop G near one edge, thus enabling it to be readily pulled off.

The pail made in accordance with this invention is of sheet-iron galvanized. All pails made in this way are drawn out of shape more or less at the top by the action of the hot metal used in galvanizing, and after being reshaped perfectly true will not retain 65 that shape, the slightest pressure or even the weight of the pail filled with water when it is hung up by the handle being sufficient to draw the top of pail out of true, thus making it impossible to use a snap-lid on the pail 70 without some device for shaping the pail and keeping the top true, as the lid would not hold itself in place unless the top remain a true circle. This is accomplished by the use of the removable cast-iron ring. The removable cast-iron ring not only serves to form 75 the recess on the inside of the pail, but reshapes the pail if it is not true when forced into its place, the soft or plastic packing keeping it in place, and the ring being made 80 of cast-iron strengthens and stiffens the pail at its mouth, so that it is always true, even when thrown on the floor, which often happens in the use of fire-pails. Again, when the pail itself is worn out the removable ring 85 may be used in a new pail and is just as available and answers the same purpose as when first used.

What I claim is—

1. In combination with a sheet-iron pail, a 90 reinforce for the top thereof comprising a removable ring with a space between the ring and the wall of the pail-body, an adhesive filling in said space and a tin-foil cover held by its edges to the filling, substantially as described. 95

2. In combination, with a pail, a wedge-shaped ring fitted to the interior thereof at its upper part and forming a space between said ring and the wall of the pail, an adhesive filling within said space and a cover held 100 by its edges to said filling, substantially as described.

3. In combination with a pail, a removable ring having a tapering lower edge fitted to the interior of the pail with a recess in the upper part of its outer wall adapted to receive an adhesive filling, a cover held by its edges to said filling and an outer protecting cover, substantially as described.

In testimony whereof I affix my signature in presence of two witnesses.

WILLIAM S. LACKEY.
